FOREIGN PATENT DOCUMENTS

IN 251822 2/2013

Primary Examiner — Cynthia Underwood(74) *Attorney, Agent, or Firm* — Robbie Webb(57) **CLAIM**

The ornamental design for a cone and channel nut, as shown and described.

DESCRIPTION

FIG. 1 is a front perspective view of a cone and channel nut of the present invention;

FIG. 2 is a front perspective exploded view of a cone nut of the present invention showing the cone and channel nut separated;

FIG. 3 is a top plan view of a cone and channel nut of the present invention;

FIG. 4 is a side elevation view of a cone and channel nut of the present invention;

FIG. 5 is a side elevation view of the cone separated from the channel nut of a cone nut of the present invention;

FIG. 6 is a front elevation view of the cone separated from the channel nut of a cone nut of the present invention;

FIG. 7 is a top perspective view of the cone separated from the channel nut of a cone nut of the present invention;

FIG. 8 is a top plan view of the channel nut separated from the cone of a cone nut of the present invention; and,

FIG. 9 is a top perspective view of the channel nut separated from the cone of a cone nut of the present invention.

No claim is made to the parts of the drawings shown in broken lines.
